(57) **CLAIM**

The ornamental design for a lens for camera, as shown and described.

DESCRIPTION

FIG. 1 is a top, rear and side perspective view of a lens for camera showing our new design;

FIG. 2 is a rear elevational view thereof;

FIG. 3 is a bottom plan view thereof;

FIG. 4 is a top plan view thereof;

FIG. 5 is a side elevational view thereof from the right of the FIG. 2;

FIG. 6 is a side elevational view thereof from the left of FIG. 2; and,

FIG. 7 discloses a lens body and camera housing both shown in broken lines to illustrate the environment only and forms no part of the claimed design.
